UNITED STATES PATENT OFFICE.

AXEL W. WAHLQUIST, OF CHICAGO, ILLINOIS.

FINISHING-MACHINE FOR THE USE OF SHOE-COBBLERS.

No. 835,586.

Specification of Letters Patent.

Patented Nov. 13, 1906.

Application filed December 9, 1905. Serial No. 291,103.

To all whom it may concern:

Be it known that I, AXEL W. WAHLQUIST, a citizen of the United States, residing at 333 Wells street, in the city of Chicago, county of Cook, and State of Illinois, have invented a certain new and useful Improvement in Finishing-Machines for the Use of Shoe-Cobblers, of which the following is a specification.

10 My improvement relates to that class of machines used by cobblers or shoe-repairers for finishing repair-work.

The object of my invention is to provide a cheap, light, compact, and portable machine 15 to be operated by foot-power, adapted to carry several cutting and polishing wheels, which can be easily adjusted and changed.

The manner in which I accomplish my object is described in the following specification 20 and illustrated in the accompanying drawings.

Figure 1 is a front elevation of the machine; Fig. 2, a side view.

The frame A, forming the main body of the 25 machine, is constructed of one piece. The lower rear part of this frame is adapted to contain a set of bearing-boxes B. Journaled in these boxes is a driving-shaft C, adapted to support a driving-wheel D. On each end 30 of this shaft a disk E is attached. Each of these disks is provided with an adjustable crank-pin F. Pivotaly attached to each of these pins is a connecting-rod G. The lower end of each of these rods is pierced with a 35 number of holes H, arranged in a vertical line. Pivotaly connected with the lower end of each of these rods is a horizontal lever I. These levers are pivotaly connected with the rear legs of the frame A and are 40 connected with a cross-bar J at the front of the frame, thereby forming a treadle. Each of the levers are pierced with a number of holes K and L, arranged in a horizontal line. These holes, in connection with the holes in 45 the connecting-rods, permit of the adjustment of the treadle both vertically and horizontally.

The upper part of the frame A is inclined 50 forward, as shown in Fig. 2, and is adapted at the upper end to support a set of bearing-boxes M. These boxes are adapted to slide vertically in the frame and to support a spindle N. This spindle is provided with a pulley O, adapted to be connected by a belt 55 or chain P with the driving-wheel and with adjustable collars Q, adapted to form bear-

ings against the boxes M. Supported on this spindle are several grinding and polishing wheels R, separated by sleeves S, which are of various lengths and adapted to slip on 60 and off the spindle and which, together with the wheels R, are secured on the spindle by the nuts T on the threaded ends of the spindle. Beneath the boxes M and pivotally attached to the frame H are two eccentric levers u, which are adapted to support the boxes M in the position required when the machine is being operated and to lower them and the spindle so the belt or chain can be removed from the driving-wheel and the 70 spindle be removed from the frame altogether. The pivot-studs v, on which these levers are supported, are adjustable vertically in the slots indicated by the dotted lines, and thereby permit the adjustment of 75 the spindle, so as to secure the desired tension of the belt or chain connecting the spindle with the driving-wheel. The stop-pin w is adapted to engage and hold the levers u in position.

80 What I claim, and desire to secure by Letters Patent, is—

1. In a machine of the kind described the combination consisting of a frame A, the lower part of said frame being adapted to 85 support a pair of bearing-boxes, a pair of bearing-boxes B supported in the lower part of said frame, a shaft C supported in said bearings and said frame adapted to be re-volved therein; a driving-wheel D supported 90 on said shaft adapted to be engaged by a belt or chain; a pair of disks E attached to said shaft, one at each end; a crank-pin F adjustable, secured in each of said disks; a pair of connecting-rods G pivotaly attached to said 95 crank-pins, each of said rods being pierced with a series of holes H arranged in a vertical line; a pair of horizontal levers I, pivotaly attached to the rear legs of the frame, and to said connecting-rods, each of said levers being pierced with series of holes K and L, said levers being connected together by a cross-bar J; a pair of bearing-boxes M supported in the upper end of the frame A and adapted to be adjusted vertically therein; a spindle N 105 supported in said boxes; a pair of collars Q adapted to hold said shaft in position in said boxes; a pulley O attached on said spindle adapted to support a belt or chain; a belt or chain P attached to and connecting said pulley with said driving-wheel; a pair of eccentric levers u pivotaly supported on said 110

- frame adapted to be moved and to support and adjust said bearing-boxes and said spindle and thereby adjust the tension of the belt or chain P; a pair of adjustable pivot-studs 5 v adjustably secured in said frame, adapted to support and to adjust the position of said eccentric levers; a pair of stops w affixed in said frame, adapted to hold said eccentric levers in position; a plurality of sleeves S, 10 adapted to slide freely over said spindle; and suitable wheels for grinding and polishing adapted to be supported on said spindle; substantially as described and for the purposes specified.
- 15 2. In a machine of the kind described the combination consisting of a frame A; a pair of bearing-boxes B, supported in the lower part of said frame; a shaft C supported in said bearing-boxes; a wheel D supported on said shaft; a pair of cranks E attached to said shaft; a pair of connecting-rods G attached to said cranks, having a series of holes H arranged in a vertical line; a pair of levers I pivotally attached to the rear legs of said 20 frame and to said connecting-rods and having boxes M supported in the upper part of said frame; a spindle N supported in said boxes 25 and provided with a pulley O and adapted to support grinding and polishing wheels R; a

belt P connecting said pulley and the wheel D; a pair of eccentric levers u pivotally supported on said frame, adapted to support and move said bearings and spindle vertically in said frame, substantially as described and for the purposes specified. 35

3. In a machine of the kind described the combination consisting of a frame A; a pair of bearing-boxes B supported in said frame; 40 a shaft C supported in said boxes; a wheel D supported on said shaft; a pair of cranks E attached to said shaft; a pair of connecting-rods G attached to said cranks; a pair of levers I having a cross-bar J; said levers being 45 pivotally attached to said frame and to said connecting-rods; a pair of bearing-boxes M supported in said frame so as to be moved vertically therein; a spindle N supported in said boxes adapted to support one or more 50 polishing-wheels R and having a pulley O; a belt P connecting said pulley and said wheel, and a pair of eccentric levers supported on said frame, adapted to support and move said boxes and spindle vertically in said 55 frame, substantially as described and for the purposes specified.
